CLAIM

The ornamental design for a beverage can cooler, as shown and described.

DESCRIPTION

FIG. 1 is a perspective view of a beverage can cooler showing my new design;

FIG. 2 is a top plan view thereof;

FIG. 3 is a bottom plan view thereof;

FIG. 4 is a side view thereof, the other sides are substantially identical;

FIG. 5 is a perspective view of an alternate embodiment of FIG. 1;

FIG. 6 is a top plan view of FIG. 5;

FIG. 7 is a bottom plan view of FIG. 5;

FIG. 8 is a side view of FIG. 5, the other sides are substantially identical;

FIG. 9 is a perspective view of an alternate embodiment of FIG. 1;

FIG. 10 is a top plan view of FIG. 9;

FIG. 11 is a bottom plan view of FIG. 9; and,

FIG. 12 is a side view of FIG. 9, the other sides are substantially identical.

The broken lines showing the can are for illustrative purposes only and form no part of the claimed design.
